UNITED STATES PATENT OFFICE.

HORACE P. CHILDS, OF TAUNTON, MASSACHUSETTS.

DESIGN FOR AN ADVERTISING DEVICE.

SPECIFICATION forming part of Design No. 13,693, dated March 6, 1883.

Application filed December 1, 1882. Term of patent 7 years.

To all whom it may concern:

Be it known that I, HORACE P. CHILDS, a citizen of the United States, residing at Taunton, in the county of Bristol and State of Massachusetts, have invented and produced a new and original Design for an Advertising Device, of which the following is a specification, reference being had to the accompanying drawings, forming a part thereof.

10 Figure 1 is a front elevation of my newly-designed device. Fig. 2 is a side elevation or edge view of the same.

This invention relates to an improved design for a revolving advertising device used 15 to exhibit bottles or packages of medicine.

In the accompanying drawings, A represents the revolving part of the device, made of circular contour on its periphery, with a circular recessed panel, B, on its front side, having 20 preferably the beveled edge C and circular recesses D in its periphery, as shown. The standard E is of substantially cylindrical form,

with a molding, F, as shown, and the base has a raised flat-topped center, G, with tapering rounded sides rounded down to the line g, 25 thence rounded down again to the base-line, as shown.

The whole design is graceful and ornamental, and proves effective in rendering popular the advertising device.

30 I claim as my invention—

The herein-described improved design for an advertising device, consisting of the part A, of circular peripheral contour, with recesses D therein, and the circular panel B at the front, the standard E, of substantially cylindrical form, with a molding, F, and the base flat-topped, and rounded down to the line g, and again rounded down to the base-line, all as shown and described.

35 HORACE P. CHILDS.
